UNITED STATES PATENT OFFICE.

MAXWELL L. REIDINGER, OF ELIZABETH, NEW JERSEY, ASSIGNOR TO THE SINGER MANUFACTURING COMPANY, OF ELIZABETH, NEW JERSEY, A CORPORATION OF NEW JERSEY.

NEEDLE-Straightening MACHINE.

Application filed May 5, 1921. Serial No. 466,872.

To all whom it may concern:

Be it known that MAXWELL L. REIDINGER, a citizen of the United States, residing at Elizabeth, in the county of Union and State 5 of New Jersey, have invented certain new and useful Improvements in Needle-Straightening Machines, of which the following is a specification, reference being had therein to the accompanying drawings.

10 This invention relates to automatic straightening machines for straightening light bars or wires and particularly sewing machine needles. The machine is of the type disclosed in the patent to Noon, No. 1,125,706, dated January 19, 1915.

One of the principal objects of this invention is to provide a machine of this type which will have a greatly increased capacity over the old type of machine in order to 20 materially increase production. This is accomplished by so arranging the straightener mechanism and the needle feeding and removing mechanisms as to reduce the time required to remove a straightened needle from 25 straightening position and placing an unstraightened needle therein.

Another object is to provide improved means for transferring the unstraightened needles to the straightening position and re- 30 moving the straightened needle therefrom, which means will be simple in construction and thus not liable to get out of order and which will be reliable in operation.

In its preferred form, the improvements, 35 comprises a plurality of separated rigid supports one of which is movable toward and from the other and is provided with a recess serving as a bearing within which the shank of the needle is revolvably held by a 40 spring pressed rotator supplying a yielding and resilient pressure thereon to secure the same in straightening position and at the same time to rotate the needle. A straightener in the form of a rapidly reciprocating 45 hammer operates upon the needle-blade between the supports and constantly close to the stationary support. This hammer is mounted on an arm extending transversely of the needle so that it and its operating 50 mechanism is located at one side of the needle to leave the spaces at the other side and in front of the needle for the needle ejecting and feeding means. This arrangement allows the various mechanisms to op-

erate simultaneously and the feeding of the 55 unstraightened needle to the support while this support is in initial straightening position so that the operation of straightening may be commenced immediately after the needle is placed in the support, thus reducing 60 to a minimum the time required between consecutive straightening operations for the removal of the straightened needle and the placing of the unstraightened needle in 65 straightening position.

The action of the hammer is governed by an impact-regulator which is preferably controlled in its operation by a feeler contacting with and deriving movements from the eccentric movements of the needle adjacent the stationary support as the needle is rotated.

The present improvement will be more fully understood by reference to the accompanying drawings in which Fig. 1 is a 75 plan view of the needle straightening machine. Fig. 2 is a sectional elevation substantially on the line of the needle. Fig. 3 is a cross sectional elevation substantially on the line 3, 3 of Fig. 1. Fig. 4 is a detail 80 sectional view of the means for moving a needle from the supply hopper. Fig. 5 is a detail view at the straightening point showing the means for transferring a needle from the hopper to the needle support immediately after a needle has been gripped by this transfer means. Fig. 6 is a view 85 similar to Fig. 5 but showing the transfer mechanism as partly advanced and with the ejector withdrawing the needle from the straightening position. Fig. 7 is a view 90 similar to Figs. 5 and 6 showing the position of the parts immediately after an unstraightened needle is clamped in straightening position. Fig. 8 is a similar view 95 showing the parts immediately after the straightening operation has begun with the transfer mechanism nearly retracted to its normal inoperative position. Fig. 9 is a detail plan view showing the elements in positions corresponding to Fig. 6, a portion of the hopper being shown in section. Fig. 10 is a plan view similar to Fig. 9 showing the needle ejector immediately after it has engaged the needle. Fig. 11 is a detail 100 sectional elevation of the mechanism for raising the friction wheel to allow for the insertion and removal of the needle. Fig. 12 is 105

a detail elevation of the hammer and means for regulating its operation. Fig. 13 is a detail of the hammer lifting mechanism. Fig. 14 is a perspective view of a hammer shaft with the striker and a portion of the hammer helve. Fig. 15 is a view similar to Fig. 14 but taken from the other side. Fig. 16 is a detail elevation of the cam for operating the needle transfer mechanism. Fig. 17 is a detail section showing a part of the transfer operating mechanism. Fig. 18 is a perspective view of the hammer head. Figs. 19 and 20 are detail sectional and end elevations respectively of a portion of the friction wheel driving mechanism. Fig. 21 is a view showing the development of the cam for producing the relative feeding movement between the needle and the straightening means. Fig. 22 is a perspective view of the end of the needle transfer bar. Fig. 23 is a perspective of the mounting for the automatic impact regulator and Fig. 24 is a detail perspective of a portion of the support for the needle rotating means.

Main drive.—The machine is constructed with a frame comprising the base-plate 1 to which are secured by means of screws 2 the feet 3 of the end standards 4 which support the bed 5 sustaining the various operative parts of the mechanism. Referring more particularly to Figs. 2 and 3 it will be noted that secured to the lower side of the bed 5 are the bearings 6 in which is journaled the cam-shaft 7 having fixed thereon the worm-wheel 8 meshing with the worm 9 secured upon the transverse main-shaft 10 mounted in bearings 11 secured upon the base-plate 1. Loosely mounted upon the main-shaft is the hub 12 of the grooved belt-wheel 13 which is encircled by a belt 14 from the source of power for rotating the main-shaft, which in this case is a second grooved pulley P on a power-shaft S.

The rearward end of the hub 12 is formed with a projecting clutch-tooth 15 adapted for engagement with the similar clutch-tooth 16 upon the adjacent face of the collar 17 fixed upon the main-shaft. From a second pulley 18 on the shaft S a belt 19 runs over the grooved belt-wheel 20 fixed upon the transverse hammer-actuating shaft 21 journaled in the spaced bearing standards 22 extending upwardly from the rear side of the bed 5, see Fig. 1. The forward end of the hub 12 of the driving belt-wheel 13 is formed with an annular groove 23 entered by the flattened head 24 of the shift-lever 25 pivotally mounted by means of the stud-screw 26 upon the post 27 rising from the base-plate 1 and affording a means of shifting the pulley 13 endwise of the driving shaft for effecting the engagement and disengagement of the clutch-members 15 and 16 so as to connect and disconnect the driving shaft 10 and its source of power at the

will of the operator. A flat spring R cooperates with a lug 25' on the under side of lever 25 to yieldingly retain the shift-lever in either position.

Hammer and its actuating mechanism.—(Figs. 1, 2, 3 and 12). The hammer-actuating shaft 21 has fixed thereon the hub 28 of the cam-wheel or trip 29 formed with a series of peripheral teeth 30 having inclined outer faces to effect a wiping engagement with the concavely curved adjacent edge of the arm 31 having a split hub 32 rigidly secured by means of the clamp-screw 33 upon the hammer rock-shaft 34 journaled in the bearing standards 22 parallel with the actuating shaft 21, said hub having projecting laterally therefrom opposite the arm 31 a second arm 35 formed in its upper side with the spaced notches 36 to receive the loop 37 at the upper end of a tension spring 38 whose lower end is attached to a staple 39 upon the bed 5. The spring 38 serves to yieldingly maintain the arm 31 in operative relation with the hammer-retracting cam-wheel 29 and assists the other parts of the hammer mechanism in producing its impact. As shown in detail in Figs. 14 and 15 the hammer rock-shaft 34 has formed integral therewith the block 40 having a lateral wing 41 to afford a striking shoulder 42, to be later referred to, and a forward extension 43.

The split hub 44 of the hammer-helve 45 is formed with the spaced ears 46 drawn together by means of the screw 47 to clamp the same upon the hammer-shaft 34, and the outer end of the helve has adjustably secured thereon the hammer-head 48 with flattened operative portion or nose 49 in the form of a separate hardened plate secured to the head 48 by means of a screw 49', the hammer-head being formed with a slit 48' leading into the aperture for the helve, and a clamp-screw 48" being applied transversely of said slit. The flattened upper side of the helve 45 adjacent the hub lies beneath the extension 43 of the block 40 and is secured thereto by means of the screw 50 passing through the part 43 and tapped into the helve, an adjusting screw 51 being tapped through the extension 43 and its point resting upon the top of the helve. By manipulation of the screws 47, 50 and 51 in a well known manner the position of the hammer-head relative to its shaft 34 may be adjusted.

It will be noted from Fig. 1 that the axes of the hammer-operating shaft 21 and the hammer shaft 34 extend substantially parallel with and to one side of the needle n so that the hammer helve 45 extends transversely of the needle and preferably substantially at right angles thereto. It is obvious by this arrangement that the hammer and its operating mechanism occupies very little space near the needle, leaving plenty of space on

the opposite side of and in alignment with the needle for the needle feeding and ejecting mechanism which will be more fully described later.

5 *Anvil.*—Adjacent the path of reciprocatory movement of the hammer is disposed the anvil or blade-support 52 formed with a wedge-shaped blunt upper extremity 53 and provided at the lower end with a flange 54 having tapped through it the adjusting screw 55 whose point rests upon the top of a block 55' set into a recess 55" in the top of the bed 5. The anvil 52 is fitted within a channel in the bearing block 56 in which it is secured by means of the clamp-screw 57 passing through a slot 58 in the bearing block and tapped into the anvil. The bearing block 56 is provided with the laterally extending feet 59 formed with the elongated apertures 60 entered by the shanks of the fastening screws 61 by which the bearing block is secured upon the bed 5 for adjustment both endwise and crosswise of the operative face of the anvil, the slots 60 exceeding somewhat in width the diameter of the screws 61.

Relative feed between hammer and needle.—One end portion of the bed 5 is formed upon its upper side with a longitudinal guideway or slideway 62 with marginal guide-bars 63 secured thereon by means of the screws 64 to overhang said slideway, within which latter is fitted the sliding carriage 65 from which depends through a clearance slot 66 in the bed a stud 67 having the anti-friction roller 68 which enters the cam-groove 69 in a cam-cylinder 70 fixed upon the cam-shaft 7, and from which the carriage receives its to-and-fro traveling movements longitudinally of the bed.

The shape of the cam-groove 69 will be seen by reference to Fig. 21, wherein the straight portion 69^a constitutes the initial dwell for presentation of the needle-blade adjacent the shank to the hammer for a succession of straightening blows in the advance position of the needle over the anvil or needle-blade support, the inclined portion 69^b produces the lengthwise feed of the needle for distribution of the hammer blows along the needle-blade, and the straight portion 69^c arrests the feed of the needle to present that portion of the blade adjacent the eye for a final series of hammer blows. After the arrest of the hammer reciprocations, the roller-stud 68 enters the abruptly inclined portion 69^d of the cam-groove to produce a rapid forward movement of the needle to initial straightening position wherein it is maintained by the straight portion 69^a while the straightened needle is ejected from the movable support or holder and an unstraightened needle inserted therein, and the initial straightening blows adjacent the shank are delivered as stated above,

after which the traverse of the roller-stud 68 through the inclined cam-groove portion 69^b causes the advance of the needle to extreme retracted position again. The dwell portions 69^a and 69^c while represented as disposed in planes perpendicular to the axis of the cam-cylinder 70, are not necessarily so related to the planes above mentioned, as a slight inclination thereof so as to correspondingly distribute the concentrated primary and final series of straightening impacts near the opposite ends of the needle-blade in contrast with the intermediate distributed series of blows may be found desirable under certain circumstances, and with needles of certain tempers. It is obviously immaterial whether the feeding movements derived from the cam-cylinder 70 be imparted to the needle-holder 74 or to the hammer and adjacent anvil, as the straightening action would be the same in either case.

Needle-support.—Upon the forward end of the carriage 65 is secured by means of screws 71 passing through apertures therein the plate 73 having projecting from its upper face the block 74 constituting the needle-shank support. The block 74 is shown provided in the top with an undercut transverse groove in which is fitted the similarly formed hardened bushing 75 having in its upper face the needle-shank receiving groove or pocket 76 (Fig. 3) of substantially V-shape in cross-section, and thus provided with outwardly and upwardly inclined forward and rearward walls to facilitate the lateral introduction and removal of the needle-shanks. The bushing 75 is secured in position by means of a clamp-screw 77 tapped into the block 74 with its point engaging the adjacent side wall of the bushing. One of the upper corners of the block 74 is cut away to form the longitudinal groove 79 transverse to the pocket 76, and to the adjacent edge of the block is secured by means of the screws 80 the stop-plate 81 whose upper edge extends somewhat above the top of the bushing 75 and which forms with the notch 79 a runway transverse to the pocket 76 the function of which will be presently described.

The needle-support afforded by the block 74 and its bushing 75 serves to sustain the shank *n'* of the needle at one side of the path of the hammer, while the anvil affords a support for the needle-blade adjacent and at the opposite side of the hammer-path. While the traveling needle-support is herein shown and described as affording a means of producing a relative feeding movement between the needle and the hammer, it is evidently immaterial to the present invention which of these members receives the actual feeding movement so long as their relation is so controlled in the operation of the machine as to effect the exposure to the

action of the hammer of different portions of the needle-blade throughout that portion of its length between the eye and the shank.

Needle rotating means.—Disposed above the needle-shank pocket in the bushing 75 is the rotary friction-wheel 82 formed with a yielding facing such as that afforded by rubber or leather, this friction-wheel being secured upon one end of a shaft 83 the axis 5 of which is inclined slightly to the needle-shank pocket 76 and to the direction of travel of the carriage 65. Secured upon the carriage adjacent the needle-support (Figs. 1, 2 and 11) is the foot 84 of the bearing bracket 85 formed with a vertical guideway 86 in which is fitted the vertically movable journal-box 87 for the adjacent end of the friction-wheel shaft 83, the bearing bracket being provided above the same 10 with an upright socket 88 having in its upper end a screw-plug 89 with lock-nut 90 between which and the top of the box 87 is interposed the spring 91 acting through the shaft 83 to press the friction-wheel 82 toward the bushing 75 and into operative engagement with the shank n' , of a needle n disposed in the groove or pocket 76. The opposite end portion of the shaft 83 is formed with a longitudinal groove 83^x. 15 (Figs. 19 and 20) entered by a spline 92 secured by means of transverse pins 93 within a bushing 94 slidably fitted upon the shaft and formed with a neck 95 which is loosely fitted to an aperture in the tilting bearing block 96 pivotally mounted by means of the pin 97 within a fork in the upper end of the post 98 rising from the bed 5. Upon the reduced outer end of the bushing 94 is secured by means of the nut 99 the pinion 100 locked against rotation thereon by means of the spline 92 and meshing with the intermediate gear 101 which meshes in turn with the actuating gear 102 fixed upon the outer end of the cam-shaft 40 20. The connection between the shaft 83 and the bearing block 96 is sufficiently loose to enable the shaft to slightly change its angular relation with the carriage under the influence of the to-and-fro longitudinal movement of the journal-box 87.

In order to permit the introduction and removal of needles in the pocket 76, provision is made for temporarily retracting or lifting the friction-wheel 82 in opposition to its spring 91. On the shaft 83 is secured a sleeve 83' beneath which extends one arm 103 of a yoke-lever fulcrumed upon the stud-screw 104 intermediate the spaced bearing lugs 105 of the bed and provided 45 with a second arm 106 formed with a depending nose-piece 107 having a backwardly and downwardly inclined operative edge adapted for engagement with the cam 108 fixed upon the cam-shaft 7 adjacent the cam-cylinder 70 and provided with a peripheral

tooth or projection 109 adapted by its engagement with the nose-piece 107 of the lever-arm 106 to lift the same and maintain it elevated for a short period in each rotation of the cam-shaft, thereby engaging the lever-arm 103 with the sleeve 83' and causing the retraction or lifting of the friction-wheel from engagement with the needle-shank. Ample clearance is thus provided for removal of the straightened needle and introduction of the unstraightened needle preparatory to a succeeding straightening operation. 70 75

To prevent the descent of the friction-wheel 82 into contact with the needle-support, the bearing bracket 85 has secured adjustably thereto by means of the screw 110 passing through a slot 111, the stop-plate 112 having a flange 113 adapted for engagement with the adjacent end of the journal-box 87 so as to limit its downward movement under the action of the spring 91. 80 85

Hammer impact regulator.—(Figs. 1, 2, 3 and 12). Secured upon the bed 5 adjacent one of the bearing studs 22 by means of screws 114 is the foot 115 of an abutment 116 formed with an inclined and circularly curved shoulder 117 toward and from which the shoulder 42 of the striker 41 moves upon the shaft 34 during the operation of the hammer. Intermediate the shoulders 42 and 117 is interposed the wedge-shaped space-block 118 constituting the active member of the impact regulator and which is sustained by means of an elastic stem 119 bent transversely from the outer end of a vibratory lever 120 the opposite end of which is secured in a slot in a round shank 121 by means of a screw 122. 90 95 100 The shank 121 is fitted to a transverse aperture 123 in a collar 124 secured to the feeler-block shaft 125 having journals at its opposite ends in bushings 126 secured by means of set-screws 127 in the spaced standards 128 of a controller bracket 129 having a foot 130 provided with elongated transverse apertures 131 entered by the shanks of the fastening screws 132 by means of which said bracket is adjustably 105 secured upon the bed 5. The shank 121 is secured adjustably within the aperture 123 by means of a set-screw 133 the shank 121 being provided with a flat surface 134 against which the end of the screw 133 110 115 rests. 120

Any suitable means may be employed for connecting the wedge-block 118 resiliently with the vibratory lever 120 but it is important that such connection be sufficiently rigid to sustain the wedge-block in its movement along the face of the abutment 117 so as to avoid as much as possible any frictional resistance to such movement. As shown more particularly in Fig. 12 the 125 130

inner face of the space-block 118 is substantially concentric with the controller shaft 125 and the adjacent face of the abutment 117 is correspondingly curved so as to enable the space-block to move as closely as possible thereof without actually touching it in its movement under the influence of the lever 120.

The rock-shaft 125 has secured thereon by means of the stud-screw 135 a block 136 to which is secured a laterally extending arm 137 at the free end of which is secured by means of a screw 138 a feeler block 139. The lever 137 is secured to the top of the block 136 by means of a screw 140 extending through a slot 141 formed in the shank of the lever 137. By means of this screw and slot connection the lever 137 may be adjusted radially of the shaft 125 to properly position the feeler block 139 with respect to the needle to be straightened. It will be noted from Fig. 12 that the upper surface of the feeler block 139 bears upon the under side of the needle *n* while the same is in straightening position. Also secured upon the shaft 125 is a block 142 to which is secured by means of a screw 143 a bent arm 144 extending under the outwardly bent end 145 of an angle-plate 146 secured to the outer vertical surface of one of the upstanding standards 128 by means of a screw 147 extending through a slot in this plate and tapped into the standard. The plate 146 in conjunction with the rod 144 provides a stop to prevent the feeler block being raised too far with respect to the position of the needle which limiting position may obviously be varied by adjusting the plate 146 upon the standards 128. A second stop 146' is adjustably secured to the vertical face of one of the bearings 22 by means of a screw 146² passing through a slot 146³. This plate has an extension 146⁴ at its upper end projecting over the lever 120. The feeler block 139 is held in contact with the under side of the needle by means of the light spring 148 the upper end of which is bent over the lever 120. The lower end is secured to the bed 5 by means of the screw 149.

As will be evident by reference to the drawings, the feeler is preferably arranged at the side of the anvil 52 or stationary needle support opposite the path of movement of the hammer and contacts or engages with the side of the needle on the opposite side from that on which the hammer operates.

Needle ejector.—On the opposite side of the needle from the hammer operating mechanism as shown in Figs. 1 and 3, is located the needle-ejector comprising a lever 150 pivoted to an upstanding bracket 151 by means of a screw 152, the bracket 151 being secured to the top of the base-plate 1. Mounted

upon pins 153 at the upper end of the lever 150 is a plate 154 on the underside of which is secured by means of screws 155 the forks 156 adapted to straddle the pins 153 and the plate 154 carries at its opposite end two rods 157 provided at their ends with downwardly bent hooks 158. The rods 157 are secured in grooves 159 formed in the upper surface of the plate 154, by means of a clamp-block 160 which is secured in position by means of a screw 161 tapped into the plate 154. By loosening the screw 161 and thus the clamp 160, the rods 157 may be adjusted on the plate 154. Secured to the body of the lever 150 by means of a screw 162 is a flat spring 163 bent so that its free end rests upon the top of the plate 154 tending to hold this plate with the hooks 158 on top of the chute and supporting elements for the needles and to engage the hooks over the needles as will be later described. Pivotally secured to the lever 150 adjacent the lower end thereof by means of the screw 164 is a link 165, the other end of which is pivoted by means of a screw 166 to a lever 167 fulcrumed on the block 168 secured to the base-plate 1. The lever 167 carries at its upper end a roller 169 contacting the edge of a cam 170 upon the shaft 7 under the influence of a spring 167² secured at one end to the lever 167 and at the other end to a pin 167² projecting downwardly from the under side of the bed 5. In certain timing relation with the needle straightening operation the hooks 158 are advanced and retracted by the spring 167 and cam 170 to withdraw a straightened needle from needle-straightening position on the block 75. When the hooks 158 are advanced one of them follows the groove 79 formed at the end of the block 75 adjacent the stop-plate 81 and because the outer ends of these hooks are curved they slide over the shank of the needle, one hook on either side of the friction wheel 82 (Fig. 6) and as this wheel is lifted before they are withdrawn, the withdrawal of these hooks will remove the straightened needle from the groove 76 in the block 75, and it passes down the inclined surface 171 into the chute 172 and is dropped into the receptacle 173 secured to the forward edge of the bed 5. Between the rear edge of the inclined member 171 and the needle supporting block 75 is a guide-block or plate 171' secured to the carriage 65 by screws 171². This block supports and guides the hooks 158 between the member 171 and the block 75.

Needle hopper.—Located on the rear of the bed 5 but at the opposite end from the sliding block 65 is located the needle-hopper 174 provided with the vertical ends 175 and 176 and inclined side walls 177 and 178 making the space within the hopper contracted at the lower end thereof. Adjust-

ably secured within the hopper is a plate 179 provided with spaced studs 180 adapted to extend through openings in lugs 181 secured to the wall 175 which lugs are provided with set-screws 182. By this construction the plate 179 may be adjusted within the hopper to provide for needles of different length from point to butt end of shank and to align the ends of the needle 10 of given length, and then secured in adjusted position by means of the screws 182. The lower open end of the hopper is closed by a segment 183 pivoted at 184 in a block 185 set in an opening in the bed 5. The upper surface of this segment 183 is formed on the arc of a circle with a center at 184 and is provided, in the present instance, with one or more shallow grooves 186 which, however, are not of sufficient depth 20 to receive the entire shank of the needle, and near the forward end thereof with a deeper groove 187 which is substantially the depth of the diameter of the needle-shank. The lower end of the support 25 183' for the segment has pivoted thereto at 188 a lever 189 provided with an anti-friction roller 190 adapted to bear against the surface of the cam 191 mounted on the shaft 7, see Fig. 4. The opposite end of the lever 189 is provided with an adjusting screw 192, the end of which abuts against the support 183' for the segment. The cam 191 as shown in Fig. 4 is provided with a plurality of shallow recesses 193 and an outwardly extending lug or projection 194. As the cam rotates the recesses 193 acting 30 upon the roller 190 oscillate the segment 183 back and forth a small amount to agitate the lower needles in the hopper slightly with the assistance of grooves 186, to insure 35 that a needle will be received within the recess 187, so that when the segment is advanced by operation of the lug 194 upon the roller 190 the needle in the recess 187 will be removed from the hopper by being 40 carried under the forward edge of the opening in the lower part thereof. A spring 195 is secured to the segment 183 at one end and to a stationary part of the machine 45 by a pin 196 at its other end and tends to hold said segment retracted in the position shown in Fig. 4.

The inclined side walls 177 and 178 of the hopper are provided with slots 197 through which may be extended a rod or bar 198 slidably mounted upon the upper end of a post 199 by means of a bracket 200, the post 199 being vertically adjustable within the bearing bracket 201 secured to 50 the forward end of the bed 5 by means of a sleeve 201' fitting in a vertical opening in the bracket 201. The sleeve 201' has an eccentric opening through it for the stud 199 and by turning the sleeve in its opening in bracket 201 the bar 198 may be ad-

justed sidewise because of the eccentric location of its opening and properly aligned with the slots 197. The bracket 200 is slidably connected with the top of the post 199 by means of a T-shaped tongue and slot 199' 70 and 199² respectively. The bar 198 is adapted to rest upon the pile of needles in the hopper and if desired a weight may be secured upon the bracket 200 to increase the pressure thereof sufficiently to insure that 75 a needle is always within the recess 187 within the upper curved surface of the segment 183 when the same is advanced to supply an unstraightened needle to the transfer mechanism which will now be described. 80

Needle transfer mechanism.—The transfer mechanism is located to reciprocate longitudinally of the needle in front of the lower end of the hopper and comprises a slide-bar 202 which is mounted to slide within a groove 203 in the upper end of a post 204 secured upon the upper surface of the bed 5 at one end thereof as shown in Figs. 1 and 2. Secured to the upper side of the slide-bar 202 is a pin 205 to which is pivoted at 206 a link 207 the other end of this link being pivoted at 208 to one end of a lever 209 fulcrumed at its opposite end at 210 to a bracket 211 secured to the end of the bed 5. Intermediate the ends of the lever 209 is a pin 212 carrying an anti-friction roller 213 adapted to follow a cam groove 214 formed within a cam cylinder 215 mounted adjacent the end of the shaft 7 as shown in Figs. 1, 2 and 16. A portion of one side 100 of this cam groove is formed by means of a block 216 adjustably secured within a recess 217 formed in the cam cylinder 215 and is adjustable therein longitudinally of the shaft by means of elongated slots 218 105 through which pass screws 219 tapped into the body of the cam-cylinder. By adjusting this block longitudinally of the shaft it will be obvious that the amount of movement imparted to the slide rod 202 may be 110 varied if desired.

Adjacent the forward end of the slide-bar 202 on its under side is secured a cam 220 adapted to contact with the upper surface of a head 221' on the top of a pin 221 115 vertically slidably in a sleeve 222 secured in an opening passing through the bed 5, the lower end of the pin 221 being adapted to bear upon the surface of the cam 223 (Figs. 2 and 17) mounted upon the main-shaft 7.

Secured to a recess in the end of the slide-bar 202 by means of a screw 224 is a clamp-block 225 which is provided with a groove 226 (Figs. 4 and 22) in the upper surface thereof adapted to receive the blade of a needle. The upper surface of the slide-bar 202 is also provided with a groove 202' (Fig. 10) in alignment with the groove 226. Pivoted within a recess 227 formed in the top 130

of the slide-bar 202 by means of a downwardly extending lug 228 and a pin 229 is a finger 230 provided at one end with a pin 231 embraced by a spring 232 resting in a recess 233 also formed in the bar 202. The other end of the finger 230 is provided with an extension 234 adapted to bear upon the upper surface of the needle-blade under the action of the spring 232 to clamp the needle 10 in the groove 202', 226 in the top of the bar 202 and block 225. Secured to the finger 230 adjacent the extension 234 and laterally projecting therefrom is a pin or stud 235 adapted when the bar 202 is retracted to the 15 position shown in Fig. 2 to rest upon the upper surface of a locating finger 236 which is substantially L-shaped and the vertical leg of which is adjustably secured to a post 237 on the bed 5 by means of a screw 238 20 extending through a slot 239 in this vertical leg.

The needle hopper is supported on the bed 5 by means of an L-shaped member 240 (Figs. 1 and 2) fastened to the bed by 25 screws 240'. Secured to the forward edge of the vertical leg of this member is a bracket 241 provided with a vertical socket 242 open at its lower end to receive a plunger 243 shouldered at 244 and provided at 30 its lower end with a roller 245 adapted to rest upon the upper surface of the slide-bar 202. Within the socket 242 is a spring 246 embracing the plunger 243 and resting on the bottom of the socket at one end and the 35 shoulder 244 at the other end thus tending to press the slide-bar 202 downwardly. This spring 246 is stronger than the spring 232 so that when the plunger 221 is allowed to assume its lowest position by the cam 223 40 the spring 246 will force the bar 202 downwardly and as the stud 235 rests on top of the L-shaped position-finger 236 the spring 232 will be compressed allowing the gripping jaws formed by the finger 230 and the 45 end of the bar 202 to open. The bracket 241 is secured to the member 240 by means of screws 247.

Setting of elements for effective operation.—In practice the needle holding and 50 straightening members may be properly set for effective operation by first inserting a perfectly straight needle in the holding support 75 and advancing the carriage 65 to bring the needle-blade above the anvil 52 55 then adjusting the top or operative edge of the anvil a few thousandths of an inch below the lower side of the needle-blade and finally setting the hammer upon its rock-shaft 34 by means of the adjusting screws 50 and 51 to bring the point or nose of the hammer head just into contact relation with the top of the needle-blade. When the hammer is at rest in its extreme lower position it is thus set at a point slightly more re- 60 moved from the plane of the face of the an-

vil than the diameter of the needle-blade. The hammer is successively lifted and released by engagement of the arm 31 with the peripheral teeth of the tripping cam 29, the hammer head being lifted to the same 70 point in each retractive movement and performing its operative stroke under the influence of its own weight augmented by the action of the spring 38 until forcibly arrested by engagement of its striker with the 75 space-block 118 interposed between the same and the fixed abutment or thrust block 116. The gyratory movements of the unstraightened needle adjacent the anvil impart to the 80 feeler arm 137 vibratory movements which are communicated to the lever 120 and transmit to the space-block 118 its operative reciprocal movements. The position of the space-block obviously determines the stopping position of the shoulder 42 of the 85 striker relative to the fixed shoulder 117 and thus determines the extent of the effective stroke, and hence the effectiveness of the blow struck by the hammer. As the determination of the hammer stroke is by this 90 means delayed until actually the instant that the blow is delivered to the needle, and as the control of its stroke is regulated by the deflection of the needle from its axis at the same instant, it will be seen that without 95 interrupting the uniform rotation of the needle the hammer impact is positioned and governed with the greatest precision.

Means for rendering the hammer ineffective.—While the needles are being introduced and removed from the needle support 75 and while they are being advanced across the anvil after they have been straightened to bring them to ejecting position it is 100 requisite that the hammer shall be maintained out of action. Instead of arresting the operation of the hammer actuating means, this is allowed to continue its action idly at such times, and the hammer is maintained in raised position by engagement of 105 its helve 45 with the notched head 248 of a vertically disposed stop bar or plunger 249 mounted for vertical movement in a tubular bearing post 250 mounted in the bed 5, its lower end being pressed by means of the 110 spring 251 against the end of an adjustable stop screw 252 mounted in the end of a lever 253. The screw 252 may be secured in adjusting position by means of a lock-nut 254. The lever 253 is fulcrumed at 255 in a downwardly extending post 256 secured to the 115 under side of the bed 5, the other end of the lever being provided with an extension 257 adapted to contact with the periphery of the lifting cam 258 fixed upon the shaft 7. This cam is formed in two sections 259 and 260 arranged side by side and formed with substantially circular peripheries having projections 261 and 262 respectively forming operative portions. The hub 263 of the pri- 120 125 130

mary section 259 is secured adjustably upon the cam-shaft 7 by means of the set-screw 264 and the hub 265 of the auxiliary section is fitted upon the hub 263 of the primary section and secured for circular adjustment thereon by means of the set-screw 266. By shifting one of these sections upon the other the effective length of the operation of the composite cam thus formed may be lengthened or shortened to produce the requisite period of inaction of the hammer which is determined by the length of the needle-blade between the eye and the shank. This cam is substantially the same as the cam used for rendering the hammer ineffective in the above mentioned patent to Noon.

The operation is as follows—

Starting with a needle in the initial position of the straightened position as shown in Figs. 1 and 2 the carriage 65 is fully advanced so that the hammer starts action upon the blade of the needle adjacent the shank and because of the dwell 69° in the cam 69 it is allowed to deliver a number of blows at the same location on the needle-blade. The friction-wheel 82 is pressed down on the top of the needle-shank under the action of the spring 91 and is being rotated through the gearing 102, 101, 100 and is thus rotating or turning the needle within the groove 76 in the block or support 75. As the roller 68 leaves the dwell 69° the carriage 65 is gradually retracted drawing the blade of the needle over the tops of the anvil 52 and the feeler block 139 and past the nose of the hammer so that a series of blows are delivered to the needle-blade throughout its length until the roller 68 reaches the dwell 69° which allows a plurality of blows to be delivered to the needle adjacent the point for the reasons stated above. During this retractive movement of the carriage 65 as the needle is being rotated its gyratory movements will impart rising and falling movements to the feeler block 139 which will be depressed more or less according to the amount of curvature in the needle, and this depression will be transmitted to the block 118 which, acting between the stop shoulders 117 and 42, will as previously explained, regulate in turn the strength of the blow of the hammer upon the needle according to the curvature in said needle. Immediately the carriage 65 reaches its extreme retracted position the hammer is raised to inoperative position by action of the cam 258 operating through the lever 253 and plunger 249. At the same time the segment block 183 closing the opening in the bottom of the hopper is advanced under the action of the cam 194 to carry a needle in the recess 187 from the hopper to a position in alignment with the jaws 234 and 225 of the transfer mechanism. The carriage 65 then begins a forward movement under the action of the cam 69, and at substantially the same time the plunger 221 is raised under the action of the cam 223 which in turn lifts the forward end of the bar 202 compressing spring 246 and allowing the finger 230 to be turned upon its pivot by the spring 232 causing the extension 234 to contact with the top of the needle-blade and clamp the same in the groove 226 in the top of the block 225 and in the groove 202' in the top of the bar 202, the location of these members being such that as soon as the blade of the needle is clamped the shank is lifted free from the groove 187 as shown in Fig. 5. The segment 183 is now retracted to its position under the hopper, shown in Fig. 4, leaving the needle clamped in the transfer mechanism. The carriage 65 continues its rapid forward movement until it reaches the extreme forward position when the ejector hooks 158 are rapidly advanced under the action of the spring 167' and cam 170 and slide over the needle-shank and hook the same as shown in Fig. 10. It will also be noted that in this figure these hook members straddle the friction wheel 82 which is still pressed upon the top of the needle-shank. This wheel is now raised under the action of the tooth 109 on the cam 108 through the lever 103 thus releasing the needle-shank and immediately the hooks 158 are withdrawn under the action of the cam 170 withdrawing the needle from the block or support 75 and it passes down the inclined surface 171 into the chute 172, and is deposited in the receptacle 173. While the straight needle is being withdrawn by the ejector mechanism, the slide-bar 202 is advanced under the action of the cam 214, lever 209 and link 207 to transfer the unstraightened needle clamped therein as illustrated in Figs. 5, 6, 7, 9 and 10 and places the shank *n'* of the unstraightened needle in the recess 76 which has just been vacated by the straightened needle. As shown in Fig. 6 as the bar 202 is advanced the cam 220 rests on the top of the post 237 thus holding the end of bar 202 elevated until the incline on the cam reaches the post when the end of the bar is allowed to gradually lower under the influence of this cam. In the position shown in Fig. 6 the shank *n'* of the needle is higher than the top of the support 75, but as the end of bar 202 is gradually lowered under the action of cam 220 the needle-shank is laid on top of the support 75 as shown in Fig. 7, the friction wheel 82 being still raised as shown in dotted lines. As soon as the shank *n'* is in position the wheel 82 is allowed to drop by the cam 108 thus clamping the needle shank within the groove. The transfer mechanism on the slide-bar 202 is immediately withdrawn releasing the needle-blade, the cam 258 at the same time allows the hammer to drop into effective 130

position and the straightening operation starts immediately. It will be thus seen that the unstraightened needle is transferred to and placed in the holding and rotating mechanism while this mechanism is in advanced position and that the straightening operation commences immediately the needle has been deposited and clamped therein. By this arrangement the mechanism and time required for the removal of straightened and the insertion of unstraightened needles, that is the time required for the ejection and feeding of the needle between the successive straightening operations, is reduced to minimum as the needle is placed in the supporting and turning mechanism in its initial straightening position.

As the bar 202 and with it the needle-clamping elements 230 and 225 are withdrawn after the needle has been placed on the support 75 as illustrated in Fig. 7, the cam 220 on the underside of bar 202 is drawn across the top of the post 237, which thus lifts the end of the bar 202 and with it the finger 230. The finger 230 is raised sufficiently, as shown in Fig. 8, for the stud 235 to pass over the top of the horizontal leg of the finger 236, and as the bar 202 is further retracted, to the left as shown in Figs. 5 to 8, the right hand end of the cam 220 passes off the top of the post 237. The plunger 221 and with it the head 221' having before this time been allowed to fall by the cam 223, when the cam 220 passes off the post 237 the bar 202 is forced downwardly under the action of spring 246 and roller 245. But as the stud 235 is arrested by the top of finger 236 in the descent of bar 202, finger 230 is turned on its pivot 229 compressing spring 232 leaving the clamping jaws open for the insertion of another needle by segment 183 as shown in Fig. 2.

The inclination of the axis of rotation of the friction wheel 82 relative to the needle recess 76 has a tendency to produce both circular and endwise movements of the needle, the endwise thrust serving to maintain the butt end of the needle-shank firmly pressed against the stop-plate 81 so as to maintain the needle in fixed position upon its travelling support, but it is obvious that this inclination of the needle rotating means might readily be employed, by omission of the stop-plate, in producing the endwise feeding movements of the needle upon a stationary support without departure from the scope of the invention.

In operation the needle-shank is held resiliently upon its travelling support by the yielding rotating member 82 to enable the needle to accommodate itself to the peening action produced by the impact of the hammer intermediate the relatively movable supports, while the blow is directed upon the

needle-blade adjacent the rigid support. 65 The relation of the cams 69 and 258 is such, however, that the blows of the hammer upon the needle-blade are concentrated around the latter adjacent both the shank and the eye at the beginning and conclusion of the endwise feeding movements of the needle beneath the hammer. 70

The cylindrical surface of the needle-shank has a bearing directly upon its support with the blade disposed very slightly 75 above the operative edge of the anvil and rotates in contact with the walls of the cavity in its support during the straightening operation so that the blade is gaged or centered with precision under the action of the hammer relative to the shank, and the needle is thus held during the straightening operation in precisely the same way in which it is ultimately secured in the needle-clamp of a sewing machine for cooperation with a loop-taker in performing the stitch-forming operations. 85

During the needle straightening operation as the carriage 65 is retracted the needle ejector hooks 158 are slowly advanced under 90 the action of the cam 170 so that when at the end of the straightening operation the carriage 65 is advanced, these hooks lie immediately in front of the needle-support or block and are arranged in such a position 95 that they may be rapidly advanced with a relatively small movement into needle gripping position.

When the machine is assembled a suitable guard 267 is secured to the bed 5 over the 100 gears 100, 101 and 102. A plate 268 is also secured over the slideway for the carriage 65 at the end thereof to prevent the entrance of dirt when the carriage 65 is advanced. There is also provided a guard over the 105 outer end of the sliding bar 202 and its operating lever and link 209 and 207, portions of this guard being represented by the reference numeral 269 and 270 in Fig. 1.

From the foregoing description it will be 110 seen that the present improvement involves principles of construction and arrangement of the various parts which are susceptible of embodiment in widely different forms and associations of parts, and that the present invention is not therefore limited to the details of construction and arrangement shown and described herein. 115

Having thus set forth the nature of the invention, what I claim herein is— 120

1. In a straightening machine, in combination, an impact-straightener, a needle-support, means for producing relative feeding movements between the straightener and the needle-support during a straightening operation and for restoring the initial relation between them after the straightening operation is completed, and means for sup-

plying a needle to said support while the elements are in initial straightening relation.

2. In a straightening machine, in combination, a needle-support, an impact-straightener, means for causing a series of separate straightening operations, means for producing relative feeding movements between the needle and the impact-straightener during each operation of the series, and means for supplying a needle to the needle-support nearly coincident with the beginning of a straightening operation.

3. In a straightening machine, in combination, a straightener, a needle-support, means for producing relative feeding movements between the straightener and the support during a straightening operation and for restoring the initial relation between them after the straightening operation is completed, means for removing the straightened needle from said support, and means for transferring an unstraightened needle to said support while the elements are in initial straightening relation.

4. In a straightening machine, in combination, an anvil, an impact-straightener adapted to operate in a path adjacent said anvil, a needle-support, a yieldingly mounted friction wheel adapted to coact with said support to secure a needle thereon and to rotate the same, means for causing relative feeding movements between the straightener and the support and for returning them to initial straightening relation, means for relatively separating the needle-support and the friction wheel while in initial straightening position to allow for the removal and insertion of a needle, means for rendering the straightener ineffective while the elements are being returned to initial straightening relation, and means for inserting a needle on said needle-support while the elements are in initial straightening relation.

45 5. In a straightening machine, in combination, an impact-straightener, a needle-support, means for retracting said support from and advancing it toward said straightener, and means for feeding a needle to said support while it is in advanced position.

6. In a straightening machine, in combination, an impact-straightener, a needle-support, means for retracting and advancing said support relative to said straightener, means for rendering said straightener effective during the retraction of said support and ineffective while the support is being advanced, means for removing a straightened needle from said support, and means for feeding an unstraightened needle to said support while it is in advanced position.

7. In a straightening machine, in combination, an impact-straightener, a needle-support, means coacting with said support

for securing and rotating a needle therein, means for retracting and advancing said support relatively to said straightener, means for rendering said straightener effective during the retraction of said support and for rendering it ineffective while the support is being advanced, means for producing relative movement between the support and said needle-securing and rotating means while the support is advanced to allow for the removal and insertion of a needle, and means for feeding a needle thereto while the support is in said advanced position.

8. In a machine for straightening needles or the like, in combination, means for supporting a needle, a hammer, an impact regulator therefor, a feeler connected with the impact regulator, an arm for supporting the feeler extending transversely of the needle, and means for distributing a series of impacts circumferentially of said needle in a straightening operation.

9. In a needle straightening machine, in combination, needle-supporting means, a hammer, an arm for supporting the hammer extending transversely of the needle, an impact-regulator for the hammer controlled by the needle at the instant of impact, and means for distributing a series of impacts circumferentially of said needle in a straightening operation.

10. In a needle straightening machine, in combination, needle-supporting means, a hammer, an arm for supporting the hammer extending transversely of the needle, an impact regulator for the hammer including a floating feeler adapted to contact with the needle, and means for distributing a series of impacts circumferentially of said needle in a straightening operation.

11. In a straightening machine, the combination with needle-supporting means, needle-rotating means, a hammer, means located at one side of the needle for supporting and operating said hammer, and an automatically acting impact regulator for said hammer comprising a movable feeler adapted to regulate the blow of the hammer according to the eccentricities in the needle.

12. In a needle straightening machine, the combination with needle-supporting means, an impact straightener, means located at one side of the needle for supporting and operating said straightener, means for distributing a series of impacts circumferentially of said needle in a straightening operation and automatic means for controlling the impact of said straightener also located at one side of the needle, said automatic means including a movable feeler adapted to contact with the needle.

13. In a needle straightening machine, in combination, a needle-supporting means, an impact straightener, automatic means for

- regulating the blow of said straightener comprising a movable feeler adapted to contact with the needle, means for supporting said feeler pivoted on an axis substantially parallel with the needle axis, and means for distributing a series of impacts circumferentially of said needle in a straightening operation.
14. In a straightening machine, in combination, needle-supporting means comprising a member provided with a recess in which the needle is adapted to rest, means for rotating the needle comprising a rotating wheel adapted to operate with its periphery contacting with the needle, a hammer for straightening the needle mounted on an arm extending transversely of the needle, and automatic means for controlling the impact of the hammer according to the eccentricities of the needle.
15. In a straightening machine, in combination, needle-supporting means, means for rotating the needle, a hammer adapted to operate on the needle and pivotally mounted at one side of the needle, a needle supply, means for removing a needle from the supporting and rotating means, and means for transferring needles from the supply to the supporting and rotating means, said removing and transfer means being located one on the opposite side of the needle from the hammer pivot and the other substantially in alignment with the needle.
16. In a straightening machine, in combination, needle-supporting means, a hammer adapted to operate on the needle and mounted on a pivoted arm extending transversely of the needle, a needle supply, means for removing the straightened needle from the support, and means for transferring an unstraightened needle from the supply to said support, one of said latter means being located at one side of the needle and the other in substantial alignment therewith.
17. In a straightening machine, in combination, a needle-support, a hammer including a pivoted arm extending transversely of the needle, an automatic impact regulator for said hammer comprising a movable feeler adapted to contact with the needle, means for holding a plurality of needles, means for transferring a needle from said holder to said support, and means for removing a needle from said support, one of said latter means being located at one side of the needle and the other in substantial alignment therewith, and means for producing relative feeding movement between the needle and hammer during a straightening operation.
18. In a straightening machine, in combination, a plurality of separated needle-supports, means whereby during the straightening operation the needle is rotated by an element having a yielding pressure upon its shank a straightener operating between said supports comprising a hammer pivoted on an axis extending substantially parallel with the needle-axis, means for removing the straightened needle from the support in a direction transversely of its axis, and means for conveying a needle to said support longitudinally.
19. In a straightening machine, in combination, a needle-support, an impact straightener adapted to operate on the needle, means to remove a straightened needle from the support and means to convey an unstraightened needle thereto, one of said means adapted to operate transversely of the needle axis and the other longitudinally thereof.
20. In a needle straightening machine, in combination, a hammer, means for rotating the needle, a feeler including a spring-pressed contact member operated by the gyratory movements of the needle-blade, an impact regulator for the hammer mechanically connected with said feeler and adapted to control the advance of the hammer toward the needle, said hammer, feeler and impact regulator being mounted to oscillate about axes extending substantially parallel with the needle axis.
21. In a straightening machine, the combination, with a straightener of separable needle-gripping members, an ejector for removing needles from between said members, an inserter for inserting needles between said members, and means for moving the inserter longitudinally of the needle.
22. In a straightening machine, the combination with a straightener, of separable needle-gripping members, means for imparting relative movement between the straightener and said gripping means longitudinally of the needle, a needle-ejector movable transversely of the needle, and a needle-inserter movable longitudinally of the needle.
23. In a straightening machine, the combination with an anvil, a hammer and hammer-actuating means, of a needle-support, means for rotating the needle including a rotary friction wheel adjacent the needle-sustaining face of said support and having an axis of rotation inclined to the needle, and means movable longitudinally of the needle for inserting a needle between the support and said friction wheel.
24. In a straightening machine, the combination with an anvil, a hammer, a hammer-actuating means, a needle-support, means for rotating the needle including a friction element with its contact surface moving transversely of the needle but at an angle thereto so as to tend to move the needle longitudinally, a stop for one end of the needle to limit said longitudinal movement, means movable transversely of

the needle for ejecting the same, means movable longitudinally of the needle for inserting the same between said support and said friction element, and means for producing relative feeding movements between the needle-support and the hammer.

25. In a straightening machine, the combination with an anvil, a hammer and hammer-actuating means, a needle-support, 10 means for rotating the needle including a friction element with its contact surface moving transversely of the needle, means for producing relative movement between the needle-support and said friction element to 15 permit the introduction and removal of a needle, and means movable longitudinally of the needle for inserting a needle between said elements.

26. In a straightening machine, the combination with a needle-support, of an anvil 20 adjustable toward and from said support, a hammer also adjustable toward and from the support and mounted to vibrate about a pivot extending substantially parallel with 25 the needle, hammer-actuating means, means for rotating the needle in the support, means controlled in its action by the deflection of the needle from its axis for varying the action of the hammer, a hopper, means at 30 one side of the needle for ejecting the same from the support, means in substantial alignment with the needle for transferring a needle from the hopper to said support, and means for producing relative feeding 35 movement between the needle and the hammer.

27. In a straightening machine, the combination with an anvil, a needle-support, 40 means for rotating the needle in the support, a hammer mounted to vibrate about a pivot substantially parallel with the needle, and means for producing relative feeding movement between the needle and the hammer, means controlled by the deflection of 45 the needle for determining the effective action of the hammer, means for determining the period of action of the hammer during the feeding operation, means whereby the length of the period of action of the hammer 50 may be varied, means on one side of the needle for ejecting the same from the support, and means movable longitudinally of the needle for placing the same on the support.

55. 28. In a needle-straightening machine, the combination with a plurality of supports upon which the needle is adapted to rest leaving an unsupported portion between them, of an impact straightener pivotally 60 mounted at one side of the needle and operating upon said unsupported portion between said supports, means whereby continuous turning movements are imparted to the needle throughout the straightening operation, means at one side of the needle 65

for ejecting the same, and means movable longitudinally of the needle for placing the same on said supports.

29. In a needle-straightening machine, in combination, a feeler contact member, an arm supporting the same and extending transversely of the needle an impact regulator connected therewith, and means for distributing a series of impacts circumferentially of said needle in a straightening 75 operation.

30. In a straightening machine, the combination, with needle-supporting means, of an anvil disposed at one side of the needle, a hammer including a head having a path 80 of movement adjacent said anvil and intermediate the latter and the needle-supporting means, and a hammer-head carrying arm extending transversely of the needle, actuating means for said hammer comprising a ratchet mounted to rotate on an axis substantially parallel with the needle, and means for producing between the needle and the hammer relative feeding movements 85 lengthwise of the needle and simultaneous 90 turning movements.

31. In a straightening machine, the combination with needle-supporting means of an anvil disposed at one side of the needle, a hammer including a head having a path of 95 movement adjacent said anvil, and a hammer-head carrying arm extending transversely of the needle, actuating means for said hammer, and an impact regulator for said hammer comprising a movable feeler element actuated by the deflection of the needle from its axis, said feeler element mounted on an arm extending transversely of the needle, and means for rotating the needle during the straightening operation. 100

32. In a straightening machine, in combination, needle-supporting means, an impact straightener, a hopper having a discharge opening, a pivoted segment closing the said opening and adapted when moved across 110 said opening to remove a needle from the hopper, and means adapted to grasp and remove the needle from the segment and deposit it on the supporting means.

33. In a straightening machine, in combination, needle-supporting means, a straightener for the needle, a hopper, means for removing a needle from the hopper, and separate means for transferring the needle from 115 said latter means to the needle-support. 120

34. In a straightening machine, in combination, a needle-supporting means, a straightener, a hopper, means for removing a needle from the hopper, means movable longitudinally of the needle for transferring 125 the needle from said latter means to the support, and means movable transversely of the needle for removing the same from said support.

35. In a straightening machine, in combi- 130

5 nation, needle-supporting means comprising separable clamping elements one of which is adapted to rotate the needle, and means for producing relative movement between said elements, needle-straightening means comprising a hammer mounted on an arm extending transversely of the needle, a needle supply, means movable transversely of the needle for removing the needle from the 10 support when the elements thereof are separated, and means movable longitudinally of the needle for transferring a needle from the supply and inserting it between said elements.

15 36. In a machine for treating needles or the like, the combination with a needle-support, of means for treating a needle, a needle receptacle, means for transferring needles from the receptacle to the support including 20 a reciprocating bar, a finger pivoted to said bar and adapted to clamp a needle thereagainst, and means operating upon reciprocation of the bar to swing the finger on its pivot.

25 37. In a machine for treating needles or the like, in combination, a needle-support, means for treating a needle, a needle-receptacle, means for transferring needles from the receptacle to said support including a 30 bar, a clamping finger pivoted to the bar, means for reciprocating the bar, and cam means operating on reciprocation of the bar to swing the finger on its pivot.

35 38. In a machine for treating needles or the like, in combination, needle-treating means, a needle-support, a needle receptacle, means for transferring needles from the receptacle to the support including a bar, a finger pivoted to the bar and adapted to 40 clamp a needle thereon, a resilient means tending to turn the finger to clamping position, means for reciprocating the bar, and means operating on reciprocation of the bar to control the effect of the resilient means.

45 39. In a machine for treating needles or the like, in combination, needle-treating means, a needle-support, a needle receptacle,

means for removing a needle from the receptacle, means for transferring the needle from said latter means to the needle support including a bar, a finger pivoted to said bar and adapted to clamp a needle, means adapted to reciprocate said bar to advance and retract the same in certain timing relation with the needle treating means, means 50 operating when the bar is retracted to hold the finger in unclamping position, means adapted to elevate the bar, and means adapted on elevation of the bar to move the finger to clamping position. 55

60 40. In a straightening machine, in combination, an impact-straightener, a needle-support, means for producing relative feeding movements between the straightener and the needle-support during a straightening operation and for restoring the initial relation between them after the straightening operation is completed, and means for endwise presenting a needle to said support in the initial straightening relation of the elements. 65

70 41. In a straightening machine, the combination with needle-shank supporting means, and an impact-straightener, a needle-hopper, means for agitating the needles in 75 said hopper to urge them into substantial parallelism, and means for endwise delivering the needles to said supporting means from said hopper.

80 42. In a straightening machine, in combination, needle-supporting means, an impact straightener, a hopper having a discharge opening, a pivoted segment closing said opening and adapted when moved across said opening to remove a needle from the 85 hopper, means for oscillating said segment to agitate the needles to urge them into substantial parallelism, and means for presenting a needle removed from said hopper to said supporting means. 90

In testimony whereof, I have signed my name to this specification.

MAXWELL L. REIDINGER.
